UNITED STATES PATENT OFFICE

HARRISON ANDERSON, OF LOS ANGELES, CALIFORNIA

BOOKHOLDER

Application filed June 15, 1929. Serial No. 371,276.

My invention relates to book holders, and it has for a purpose the provision of a book holder particularly adapted, although not necessarily, for holding a book upon or in close proximity to a desk or other horizontal support and in closed and open positions, the holder in its association with a desk functioning to support the book in open position on top of the desk, and when not in use in closed position at one side of the desk.

It is also a purpose of my invention to provide a book holder having a book holding frame, the parts of which are movable relatively to permit the frame to occupy open and closed positions and the book contained therein, corresponding positions, and a supporting structure for the frame by which the frame as a unit is movable vertically to occupy an elevated position at the top of the desk and a lowered position at one side of the desk. The supporting structure includes a foldable bracket, which, when extended, operates to support the book holding frame in elevated position, and a mechanism operable by movement of the frame to open position for maintaining the bracket in extended position and for folding the bracket when the frame is closed, to permit the latter to be moved to lowered position.

I will describe only one form of book holder embodying my invention, and will then point out the novel features thereof in claims.

In the accompanying drawings:

Fig. 1 is a view showing a part of a desk having applied thereto, one form of book holder embodying my invention, the holder being lowered and closed and without a book to disclose parts not otherwise revealed.

Fig. 2 is a view similar to Fig. 1 showing the book holding frame in elevated position and open.

Fig. 3 is a view showing the book holder in side elevation and in applied position to a desk.

Fig. 4 is a view similar to Fig. 3 but showing the holder in elevated position and the book holding frame open.

Fig. 5 is a fragmentary sectional view

taken on the line 5—5 of Fig. 4 and looking in the direction of the arrows.

In carrying out my invention, I provide a book holder adapted to be associated with a desk or similar form of office furniture, for holding a book such as a telephone directory in open position at the top of the desk, as illustrated in Fig. 2, and when not in use, in closed position at one side of the desk, as illustrated in Fig. 3. As best illustrated in Fig. 4, a pair of blocks 15, preferably of wood, are secured to the side of a desk 16, and in spaced relation to each other, the blocks being spanned by a metal plate 17 provided with an upwardly curved slot 18 where it spans the blocks 15 and in which slot operates a pin or bolt 19. This pin 19 is secured to an L-shaped bracket 20 which in turn is secured to the under side of the back section 21 of a book holding frame. The back section 21 is mounted at one end on an angle bar 22 secured to the plate 17, a hinge 23 being employed for the purpose. The association of the hinge 23 with respect to the angle bar 22 and the back section 21 is such that the back section is supported for swinging movement vertically to occupy the lowered position shown in Fig. 3, or the elevated position shown in Fig. 4. In moving the back section to either of these two positions, the pin 19 rides in the slot 18 and thus serves to restrict movement of the back section in a vertical path, as well as to relieve the hinge 23 of any lateral stresses.

As previously stated, the back section 21 forms a part of a frame in which a book is adapted to be held, side sections 24 and 25 being mounted upon the back section 21 by means of hinges 26 and in such manner as to permit the side sections to occupy open and closed positions. When in open position, the side sections serve to support also the halves of a book in open position, while when in closed position they embrace the sides of the book and thus coact with the back section to support the book in vertical and closed position at one side of the desk.

For retaining a book within the holding frame, I employ a retaining means which is identical to the retaining means embodied in

my application, book holder, Serial No. 371,274 filed June 15, 1929. Consequently, a brief description of the retaining means is thought to suffice. This means comprises two sets of prongs 27 and 28, the former being fixedly associated with the back section 21, while the latter is removable to facilitate the insertion and removal of a book to and from the frame. These prongs 27 and 28 are adapted to be projected between the leaves of the book and when the prongs 28 are secured in fixed position, the book is securely attached to the back section.

As best illustrated in Figs. 3 and 4, the book holding frame is adapted to be supported in elevated position by means of a bracket including a pair of channelled links 29 and 30, hingedly connected to each other and to the back section 21 and the angle bar 22. As shown in Fig. 2, a spring 31 is connected to the links 29 and 30 so that when they are moved to extended position, the spring acts to maintain them in such position, but once the links are folded, the spring acts reversely and to maintain the links in folded position. By the provision of a lever 32 pivoted on the back section 21, the upper link 30 can be moved upwardly to break the joint between the links so that the bracket can be moved to folded position and the book holding frame moved to lowered position. This lever 32 is provided with an extension 33 which is engaged by a leaf spring 34 secured to the back section and operating to urge the lever upwardly so that it tends to actuate the upper link 20 to collapse the bracket. A cam 35 is secured to the side section 25 so that when such section is moved to open position the cam will engage the extension 33 and force the lever 32 downwardly against the action of the spring 34, in consequence of which the lever is prevented from acting to collapse the bracket.

From the foregoing construction, it will be manifest that the lever 32 normally acts to collapse the bracket formed by the links 29 and 30, but that in the open position of the side section 25, the cam 35 functions to render the lever 32 inactive, so that once the bracket is moved to extended position it will maintain such position under the action of the spring 31. Conversely, when the side section 25 is moved to closed position, the cam disengages the extension 33 so that the spring 34 is free to actuate the lever 32 to collapse the bracket and thus permit lowering of the frame to its normal position. The frame in its movement to lowered position, is guided by an arm 36 secured to the angle bar 22, and the side sections 24 and 25 of the frame together with the book contained therein are urged in the direction of the arm 36 by means of a leaf spring 37 secured to the outer side of the side section 25. This spring 37 has sliding contact with the plate 17. However,

the primary purpose of the arm 36 is to engage, move, and hold the side section 24 in closed position as the book holding frame is moved to lowered position, so that once the frame reaches lowered position, the frame will be retained in closed position at one side of the desk. The lowermost position of the frame is defined by means of a yoke 38 secured to the angle bar 22 and engaging the back section 21. This yoke 38 may be constructed of spring steel so as to cushion the frame in its movement to lowered position and to thereby prevent injury to any of its parts.

In the operation of the book holder, it normally occupies the lowered position shown in Figs. 1 and 3, and in which position the frame is closed to embrace and hold a book in closed position at one side of the desk. When desiring to gain access to the book, the holding frame is lifted to elevated position in which the side sections 24 and 25 are free to swing to open position, it being understood that in moving the frame to elevated position, the side sections are extended beyond the confines of the plate 17 and the arm 36. As previously explained, movement of the side section 25 to open position actuates the cam 35 to prevent the lever 32 from actuating the upper link 30 so that the foldable bracket is maintained in extended position and thus the frame is held in elevated position. In the open position of the frame, any page of the book may be referred to, the side section 25 being extended over the top of the desk to support one-half of the book, and the other side section 24 extending to one side of the desk and supporting the other half of the book. Thus, the book is supported in convenient position for reading.

To return the book to normal position at the side of the desk, it is only necessary to close the frame as then the cam 35 functions to collapse the links 28 and 29, whereby, the frame may be lowered vertically at one side of the desk and retained in closed position.

Although I have herein shown and described only one form of book holder embodying my invention, it is to be understood that various changes and modifications may be made herein without departing from the spirit of the invention and the spirit and scope of the appended claims.

I claim:

1. A book holder, comprising a book holding frame capable of occupying open and closed positions, means connected to the frame for supporting the latter for swinging movement about a horizontal axis to occupy lowered and elevated positions, a collapsible bracket for supporting the frame in elevated position, means acting to collapse the bracket, and means operatively connected to the frame for rendering the collapsing means inactive when the frame is in open position.

2. A book holder, comprising a plate adapted to be secured to a vertical support, an angle bar secured to the plate, a book holding frame including a back section hingedly mounted on the angle bar, a pin and slot connection between the back section and the plate for limiting upward movement of the back section around the angle bar pivot, said frame including side sections hingedly mounted on the back section, a collapsible bracket also connecting the back section and angle bar, means on the bracket tending to maintain the latter extended when moved to extended position, a lever on the back section operable to collapse the bracket against the action of said means, a spring on the back section tending to actuate the lever to collapse the bracket, and a cam on one of the side sections operable by movement of the side section to open position to move the lever to a position in which it is ineffective to collapse the bracket.

3. A book holder as embodied in claim 2 wherein one of the side sections is provided with a spring positioned to have wiping contact with said plate when the frame is moved downwardly for holding the side section in closed position, and an arm on the angle bar to engage the other side section for holding the latter in closed position.

4. A book holder, comprising a support, a book holding frame including a back section hingedly mounted on the support and side sections hingedly connected to the back section to occupy open and closed positions, a collapsible bracket connecting the back section and support, means on the bracket tending to maintain the latter extended when moved to extended position, a lever on the back section operable to collapse the bracket against the action of said means, a spring on the back section tending to actuate the lever to collapse the bracket, and a cam on one of the side sections operable by movement of the side section to open position, to move the lever to a position in which it is ineffective to collapse the bracket.

5. A book holder, comprising a book holding frame including a back section and side sections hingedly mounted on the back section to occupy open and closed positions, a support for the frame, a hinged connection between the support and back section for supporting the frame for movement in a vertical plane, a collapsible bracket connected to the support and to the back section for supporting the frame in elevated position, means provided on the back section which constantly acts to collapse said bracket, and means on one of the side sections operable to engage a part of the first mentioned means upon movement of the side section to open position and to thereby render said first mentioned means inactive to collapse the bracket.

6. In a book holder, a vertical plate adapt-

ed to be fixed to an article of furniture, the said plate having an upwardly curved slot, a hinge carried by the plate, the said slot being concentrically related to the pintle of the hinge, means connected with the hinge for supporting a book, a pin carried by said means and operating in said slot, and means co-operable with the plate and with the first said means for holding the latter in a relatively fixed position of tilted adjustment.
